(57) **CLAIM**

The ornamental design for an auxiliary table and convenience chest for hospital beds, as shown and described.

DESCRIPTION

FIG. 1 is a perspective view of an auxiliary table and convenience chest for hospital beds showing my new design;

FIG. 2 is a front elevation thereof;

FIG. 3 is a rear elevation thereof;

FIG. 4 is an elevational view thereof as seen from the right-hand side of FIG. 1;

FIG. 5 is an elevational view as seen from the left-hand side of FIG. 1; and,

FIG. 6 is a top plan view.

1 Claim, 4 Drawing Sheets

FIG.1

FIG. 4

FIG. 5

FIG. 6
